UNITED STATES PATENT OFFICE.

RILEY E. CANNON, OF LEXINGTON, KENTUCKY.

DESIGN FOR WRITING-PEN.

Specification forming part of Design No. 7,968, dated December 29, 1874; application filed December 14, 1874.
[Term of Patent 14 years.]

To all whom it may concern:

Be it known that I, RILEY E. CANNON, of Lexington, in the county of Fayette and in the State of Kentucky, have invented certain new and useful Design for Reversible Pens; and do hereby declare that the following is a full, clear, and exact description thereof, reference being had to the accompanying drawings, and to the letters of reference marked thereon, making a part of this specification.

The nature of my design for writing-pens is fully illustrated in the accompanying drawings, in which—

Figure 1 is a top or plan view, and Fig. 2 a longitudinal section.

a represents the body of the pen, made of a single piece of metal, and having a pen-point, *b*, of usual form, at each end.

The pen is made on the usual curve for in-

sertion in the pen-holder. Extending across the center of the pen is a swell, *c*, and at each end of each side of said swell is a notch, *x x x*, as shown.

This design constitutes an ornamental, distinguishable, and highly useful pen.

What I claim is—

The design for a reversible pen, consisting essentially of the two points *b b*, a central swell, *c*, and notches *x x* at each side of each end of the swell, substantially as shown.

In testimony that I claim the foregoing I have hereunto set my hand this 8th day of December, 1874.

RILEY E. CANNON.
